CLAIM

We claim the ornamental design for the digital signage device, as shown and described.

DESCRIPTION

FIG. 1 is a rear perspective view of a digital signage device showing the new design;

FIG. 2 is a rear elevation view thereof;

FIG. 3 is a front elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines depict parts of the digital signage device that form no part of the claimed design.
